UNITED STATES PATENT OFFICE.

WILLIAM B. GETTY AND DAVID BRICKER, OF HICKSVILLE, OHIO.

STOVE-PIPE DRUM.

SPECIFICATION forming part of Letters Patent No. 274,117, dated March 20, 1883.

Application filed January 25, 1883. (No model.)

To all whom it may concern:

Be it known that we, WILLIAM B. GETTY and DAVID BRICKER, citizens of the United States, residing at Hicksville, in the county of 5 Defiance and State of Ohio, have invented a new and useful Stove-Pipe Drum, of which the following is a specification, reference being had to the accompanying drawings.

This invention relates to stove-pipe drums; 10 and it consists essentially in certain improvements in the construction of the same, which will be hereinafter fully described, and particularly pointed out in the claim.

In the drawings hereto annexed, Figure 1 is 15 a vertical sectional view of a stove-pipe drum equipped with our improvements. Fig. 2 is a horizontal or transverse sectional view of the same on the line *xx* in Fig. 1, and Fig. 3 is a perspective view of the damper removed from 20 the drum.

The same letters refer to the same parts in all the figures.

In the drawings hereto annexed, A designates a stove-pipe drum, which consists of a 25 body, B, having a detachable cap or upper section, C. The upper end of the body B is provided with vertical slots D, forming bearings for a transverse shaft, E, having collars F, by which it is retained in its bearings, and provided at one end with a crank, G, by means 30 of which it may be conveniently turned. The cap C, when in position, retains the shaft securely.

H is a disk or damper secured to the shaft 35 E inside the drum or casing. The sides of the said disk or damper are provided with slots I, at the sides of which are secured lugs J, between which downwardly-depend ing rods K are pivoted. Between the said rods, at suitable distances apart, are pivoted similar disks 40 or dampers, L L, of which there may be any number desired. The sides of the dampers H and L are cut away alternately on opposite sides, as shown at M, so that even when the 45 dampers are in a horizontal position they will admit of the passage of the products of combustion from the stove, to which the device is applied by the latter taking a zigzag course between the dampers. By turning the shaft 50 E all of the disks or dampers may be turned

simultaneously to a vertical or to a horizontal position, as required, within the drum or pipe. The uppermost disk or damper, H, is provided with a slide, N, having pins O O, working in guide-slots P in the said disk, and having an 55 operating-rod, Q, extending through a perforation in the collar at the outer end of the shaft E, and provided with a knob or handle, R. The said slide may be moved out, so as to cover the opening M at the edge of the disk 60 or damper, and thus obstruct the passage of the products of combustion when it shall be desired to do so.

The operation and advantages of our invention will be readily understood from the foregoing description, taken in connection with the drawings hereto annexed. By manipulating the crank-shaft the dampers may be readily adjusted so as to permit the products of combustion to pass freely, or so as to check their 70 passage by compelling them to take a zigzag course. By operating the slide N their passage may be entirely prevented.

This invention is applicable to ordinary stove-pipes by fitting the shaft E at the joint 75 between two sections of pipe.

We claim as our invention and desire to secure by Letters Patent of the United States—

The combination of a stove-pipe or drum, a shaft journaled transversely in the same and 80 provided with collars to hold it in position, a series of dampers having alternately cut-away sides and connected by pivoted rods, one of the said dampers being secured to the said shaft, and a slide mounted upon the damper 85 thus secured and having an operating-rod extending through a perforation in the collar at the outer end of the transverse shaft, whereby the said slide may be manipulated so as to cover the cut-away side of the said damper, as 90 set forth.

In testimony that we claim the foregoing as our own we have hereto affixed our signatures in presence of two witnesses.

WILLIAM B. GETTY.
DAVID BRICKER.
